J. REIDEL.

Cartridge.

No. 15,707.

Patented Sept. 9, 1856.

UNITED STATES PATENT OFFICE.

JULIUS RIEDEL, OF PLEASANT HILL, KENTUCKY.

IMPROVEMENT IN CARTRIDGES.

Specification forming part of Letters Patent No. 15,707, dated September 9, 1856.

To all whom it may concern:

Be it known that I, JULIUS RIEDEL, of Clay Viaduct, Pleasant Hill, in the county of Mercer, in the State of Kentucky, have invented a new and Improved Cartridge, filled with shot or other balls, for fire-arms of any description, for the purpose of far and accurate shooting; and I do hereby declare that the following is a full and exact description thereof.

The nature of my invention consists in making a cartridge in shape of a pointed ball, giving it the greatest possible weight, and strength sufficient to resist the expanding power of its contents to a more distant point than cartridges generally do, operating like a ball (or pointed ball) until the expansion of the contents causes it to burst, thereby giving free egress to the inclosed shot or balls. By this arrangement a greater result is effected than without the aid of said cartridge. This pointed ball-cartridge adds to the common distance of effective shooting by shot-guns one-third to one-half. For rifles of large bore, and pistols, in point of certainty and distance, its advantage is far greater; and it is believed the same will be true for pieces of ordnance.

The shape of this cartridge is to be that of a cone, with a hemispherical base, or nearly so; for shot-guns, rifles, and pistols, this base is made of heavy sheet-lead or other substance, and connected with a cone made from good stiff paper. The connection between the hemispherical base and cone is made by an envelopment of linen or muslin or other substance, which shall serve the purpose of attachment, being regulated in strength by the distance at which it is required that the cartridge should burst. It is believed the development of the cone most suitable in shape would be the quarter of a circle, allowing a little for lapping. After the outside of the cartridge is thus made, it is to be filled by shot or balls. This can be done in many ways, but it is believed that it would be best effected by a slight aperture near the point of the cone,

to be closed subsequently by pasting paper over the aperture. If applied to pieces of ordnance, other substances would be employed to form the cartridge of more strength.

To use the cartridge, the hemispherical end is put first into the gun, or downward, the cone pointing outward. In this position it is rammed home. To prevent destroying the shape of the cone, it would be necessary to have a conical cavity corresponding to the cartridge in the ramrod, but for dispensing with this alteration, I deliver a short cylindrical ramrod-link-piece, adapted to every size of cartridge separately. When the cartridge is fired, as soon as it leaves the gun it turns, the hemispherical end going forward in consequence of its greater weight, the conical portion serving to keep its direction; after going a considerable distance it will burst, by the tendency of the contents on the inside to expand.

I claim making the pointed ball-cartridge as above described, and as shown by the accompanying drawings.

I claim—

1. As novel that the shape of my cartridge is such that one end is naturally loaded heavier than the other, as represented by section *a c b d*, thereby causing that end to go forward, thus guarding against all revolving motion except a simple winding or peristaltic one.

2. The constructing the hemispherical end of the cartridge stronger and heavier than the conical end, having several objects in view, viz: That the loading of shot or balls on the inside may be kept together a considerable distance after leading the gun; that the lighter conical end may serve to keep the whole in the given direction till the cartridge is burst, and, when burst on or near its base, give free egress to its contents.

JULIUS RIEDEL.
